HERMANN V. FENGLER, OF WEST PHILADELPHIA, PENNSYLVANIA, ASSIGNOR TO
UNDERWOOD TYPEWRITER COMPANY, OF NEW YORK, N. Y., A CORPORATION OF
DELAWARE.

TYPE-WRITING MACHINE.

1,256,303.

Specification of Letters Patent. Patented Feb. 12, 1918.

Application filed July 9, 1915. Serial No. 38,853.

To all whom it may concern:

Be it known that I, HERMANN V. FENGLER, a citizen of the United States, residing in West Philadelphia, in the county of 5 Philadelphia and State of Pennsylvania, have invented certain new and useful Improvements in Type-Writing Machines, of which the following is a specification.

This invention relates to typewriting machines, specially constructed to facilitate the making of typewritten entries on bills or other work-pieces which are placed *seriatim* on the machine, each bill being removed from the machine after the record 10 has been made thereon, before the succeeding bill is placed on the machine, while a record sheet is retained on the machine to receive the record copy of a number of succeeding bills. In machines designed for 15 such use it is customary to provide an operator or driver having a releasable driving connection with the platen, whereby the driver when moved in one direction rotates the platen backwardly or in an anti-line- 20 feed direction into position to receive a succeeding bill when the completed bill has been removed, so that the return movement of the driver will rotate the platen forwardly and advance the new bill into position 25 to be written upon. The forward rotation of the platen by the driver is through a somewhat greater distance than the backward rotation, in order to suitably space on the record sheet, the record copies of succeeding bills. The driver while in its 30 normal position of rest is disconnected from the platen to permit the latter to be rotated independently thereof, while the typewritten entries are being made.

40 The present invention provides an improved mechanism for operating the platen in positioning the work-pieces thereon and removing them therefrom. In accordance with this invention, the return movement of the driver and the forward rotation of the platen as the driver is returned, may be 45 automatically effected by a motor, conveniently in the form of a spring motor, wound by the driver during its forward stroke. As the platen is rapidly rotated by the motor, there is a tendency for it to 50 overthrow or be carried beyond its normal stop position as the driver completes its return movement and is disconnected from the platen. To prevent such overthrow, the

invention provides means to effect a complete stop of the driver and platen before the driver is disconnected from the platen, whereby said tendency to overthrow is entirely overcome.

In practising the invention, the driver may be loosely mounted for rotation on the platen axle and may have a speed-multiplying driving connection with the platen by means of a band connecting the driver with 60 a dog-carrying member rotatable about the platen axis, the dog being movable into and out of driving engagement with a platen-driving toothed wheel or rack connected to rotate with the platen. The dog is normally 65 spring-held off said wheel, to permit independent rotation of the platen. Shortly after the driver commences its advance movement, the dog is cammed into driving engagement with the driving wheel and 70 held thereon during the forward and return movements of the driver. The means for holding the dog in operative position may comprise a stationary section. (as for 75 example, the peripheral wall of a casing 80 inclosing the drive wheel and dog) and a movable section operative to hold the dog against its wheel only when the dog, during the return movement of the driver, has passed beyond the point at which, during 85 the forward throw of the driver it was engaged with said wheel, whereby the rotation of the platen during such return movement is through a greater distance than its rotation during the advance or forward throw 90 of the driver. When the driver has been returned by its spring to starting position, the movable dog-holding section is automatically thrown to inoperative position to thereby release the dog, so that the platen 95 may be rotated independently of the driver. Such movement of the dog-holding section is effected by a throw-off device actuated by a weighted trip or kicker, carried by the driver. Said kicker may be connected with 100 the driver by flexible means, as a leaf-spring, permitting the kicker to be vibrated by its inertia. As the driver is completing its return movement, said kicker is carried past said throw-off device, and owing to its 105 momentum acquired by the rapid return of the driver, is thrown forward beyond its normal position, when the driver is stopped, and then swings or kicks backward, thereby actuating the throw-off device to swing the 110

movable dog-holding section off the dog, and release the latter from its wheel. The driver is brought to a full stop and thereby stops the platen before the kicker operates

5 to release the dog, so that any tendency for the platen to overthrow is overcome. When the driver is again advanced, the dog, (which holds the movable section out of operative position) moves idly until it passes 10 beyond the said section, and is then reengaged with the driving wheel and permits said movable section to be returned to operative position.

The distance through which the platen 15 is rotated at each operation of the driver may be adjustably controlled by a tape which may also serve as the platen-driving spring, for which purpose one end of the tape may be connected to the dog-carrying 20 member and the other end connected to an adjustable stationary member. The latter may consist of a cap or end plate for the casing within which said tape, the dog and the driving wheel are contained; said end 25 plate may be rotatably adjustable and suitably held at line-space intervals, a graduated scale being provided with index numbers to indicate for any adjustment, the number of line-space distances through which the 30 platen may be advanced by an operation of the driver.

This present application shows certain features also disclosed in my co-pending application, Serial No. 27,303, filed May 11, 35 1915.

Other features and advantages will hereinafter appear.

In the accompanying drawings:

Figure 1 is a perspective view of a carriage of an Underwood typewriting machine, showing my invention as applied thereto.

Fig. 2 is a perspective view of the driver.

Fig. 3 is a front elevation, showing some 45 parts of my improved device in section.

Fig. 4 is a part sectional plan view, showing the movable dog-retaining section tripped to release the dog.

Fig. 5 is a disassembled perspective view 50 of parts of my improved device.

Fig. 6 is a fragmentary perspective view of the adjustable cap and the spring for holding said cap as adjusted.

Fig. 7 is a side elevation showing the 55 parts after they have been returned to normal position, the tripper having caused the driving dog to be released.

Fig. 8 is a side elevation, showing the driving lever advanced to a point where the 60 dog has engaged the gear and rotated it a slight amount.

Fig. 9 is a side elevation, showing the relative position of the parts as the driver has about completed its return movement.

65 Fig. 10 is a sectional side elevation show-

ing my improved paper guide, and also showing diagrammatically the means for feeding and holding the work-sheet with the platen.

The usual platen 1 of an Underwood type- 70 writing machine is rotatably mounted on an axle 2 in the end plates 3 of the platen frame, the ends of the axle 2 projecting past the said end plates and having finger-wheels 4 fast thereon, by which the platen may be 75 rotated forwardly or backwardly to an unlimited extent for inserting, adjusting, or removing work-sheets. The platen may also be rotated in line-feed direction by the usual line-spacing mechanism comprising a line- 80 space lever 5 to operate a slide 6 carrying a pawl 7, which engages a ratchet wheel 8 fast on the platen axle.

The platen may be rotated to bring the work-sheets around to position to receive 85 impressions from types 9, by the finger-wheels 4, or by repeated operations of the line-spacing mechanism, the work-sheets being held against the platen by the usual feed rolls 10 and 11 (Fig. 10).

In making out bills and the like, it is customary to make at the same time a record copy of the data on each bill. This record copy is usually made on a sheet considerably larger than the bills, so that the data of a 95 number of bills may be placed on one sheet. The bill and record sheet and the carbon for the record sheet are usually placed on the machine and moved around to the printing point of the machine together. 100

After the bill has been written the feed rolls 10 and 11 are moved away from the platen in the usual manner, and the bill with its carbon sheet is drawn out of the front of the machine by hand. The record 105 sheet is held to the platen during the removal of the bill by the usual paper finger rolls 12.

When the bill has been removed from the machine it is desired to move the record 110 sheet back to bring the last typewritten line thereon into such a position that when the platen is rotated to bring the next bill into printing position, the first line of writing thereon will closely follow on the record 115 sheet, the last line of the succeeding bill.

In providing an improved device for moving the platen backwardly to thus receive the new bill, a driving lever 13 loosely mounted on the platen axle 2 is provided at 120 its upper end with a stud 14 to which a metal band 15 is attached. The band 15, extends downwardly from the stud 14 and is guided over a pulley 16 on a bracket 17 fixed to the end plate 3. From said pulley 125 the band extends through an opening 18 in the casing 19 of the mechanism and is wound on and fastened to a member 20 loosely mounted on the platen axle. The member 20 is provided with a flange portion 130

21 upon which a leaf-spring 22 carrying a dog 23 is fast.

When the dog-carrying member 20 is rotated during the first part of the forward movement of the driver 13, the dog 23 strikes against a cam surface 24 at an opening 25 in the casing 19 and is forced, as shown in Fig. 8, against the tension of its spring 22, through an opening 26 in the flange 21 into engagement with a gear 27 fast on the platen axle 2. The dog 23 is held in engagement with the gear 27 by the inner surface of the casing 19, thus causing the platen to be coupled with and driven by the dog-carrying member 20 which in turn is connected to be rotated by the driver 13 through the band 15.

The driver 13, thus connected to the platen, when drawn forward to move the record sheet backwardly, is stopped at the desired position to receive a new bill and carbon sheet, by a tape or band which may be in the form of a clock spring 28 having connections to the dog-carrying member 20 and the casing 19, whereby the rotation of the dog-carrying member having fully wound the tape 28 is stopped thereby. The tape 28 has its inner end fast to a hub 29 of a disk 30 loosely mounted on the platen axle 2 and connected to the dog-carrying member 20 by means of projections 31 on the disk 30 which enter notches 32 in the dog-carrying member 20 when the parts are assembled. The outer end of the tape 28 is held against movement by a pin 33 on a disk 34 which may form a cap for the casing 19, said tape 28 having a looped portion 35 which may be slid over said pin 33.

In making out bills or the like, worksheets having printed headings of various sizes may be used. As it is not desired to write on these headings, the platen with the record sheet must be rotated backwardly sufficiently to bring the last line of writing done on the last bill and the first line of writing on the new bill close together on the record sheet. Thus the mechanism for stopping the platen must be varied according to the number of line-spaces the first line of writing on the bill is from the top edge of the bill.

In order to vary the stopping point of the platen, or in other words, to vary the length of throw of the driver, the cap 34 carrying the floating end of the spring 28 is mounted 55 to be angularly adjustable, whereby the spring 28 may be wound or unwound as desired to either increase or decrease the extent of rotation that can be given to the platen before it is stopped. The cap 34 is normally held against the casing 19 by a spring 36 which forces a projection 37 on the cap into one of a series of notches 38 on the casing 19, said projection holding the cap 34 in its adjusted position. To adjust 60 the stopping device for a billhead, for in-

stance, one having a heading of ten line-spaces, the operative grasps the cap 34 by its knurled edge, moving it endwise against the tension of the spring 36 until the projection 37 is free from the notches 38, then 70 rotates the cap until the number "10" of a scale 38a on the cap comes into register with an index pointer 40 on the casing 19. The operative then allows the spring 36 to move the cap against the casing so that the projection 37 will enter the notch 38 with which it is in register.

After the record sheet has been moved back, the new bill and its carbon sheet are placed on the machine behind the record sheet, to be fed forward to the printing position on the return movement of the driver 13. To facilitate the insertion of the bill and carbon sheet, the record sheet is held away from the paper table by blocks 41 85 which may form part of, or may be removably attached to lateral guide plates 42, adjustably mounted on the paper table. The guide plates 42 are provided with upwardly extending flange portions 43 which form 90 gages for the lateral edges of the record sheet while the inner vertical faces 44 of the blocks 41 serve as lateral guides to the bills and carbon sheets. Thus it will be seen that with the record sheet held off the paper table, the 95 bill and carbon sheet may be placed on the paper table and allowed to drop free from any interference of the record sheet, into position to be gripped between the platen and feed rolls, and to be fed around to position to receive type impressions with the record sheet.

While inserting new sheets, the operator retains the driver 13 in its forward position against the tension of a spring 45. This 105 spring is wound on a hub portion 46 of the dog-carrying member 20, having its inner end fast thereto and having its outer end provided with a loop portion adapted to be slipped over a pin 46a on the casing 19 110 when the parts are assembled. This spring is wound by the forward movement of the driver 13, and serves as a motor for returning the driver and turning the platen forwardly, that is, in line-feed direction. 115 When the operator releases the driving lever 13 after the work-sheets have been placed on the machine, the spring motor 45 rotates the dog-carrying member 20 and drives the platen through the dog 23 and 120 gear 27 in line-feed direction, until the driver 13 is stopped by the bracket 17 which is fixed to the end plate 3 of the platen frame. The dog is held in engagement with the gear during part of the return movement of the driver, by the inner periphery of the casing 19, and during the final portion of said return movement by a movable section, trap or gate 47, which extends across 125 the opening 25 in the casing. The movable 130

section 47 having an arm portion 48 pivoted to the casing 19 and being guided beneath a block 49 at its other end normally tends to move over the opening 25, being urged by a spring 50 bearing against a pin 51 on said section. The movement of the section 47 about its pivot may be limited by the block 49.

After the platen and driver have been stopped by the bracket 17, a block 52, carried with the driver, but movable relatively thereto as by means of a connection comprising a leaf spring 53 fixed to an arm 54 on the driver, is caused by its inertia to vibrate. The block 52 carries a downwardly extending pivoted dog 55 adapted to operate a releasing arm 56 pivotally mounted on the block 49. As the block 52 moves forward, the dog 55 strikes the releasing arm 56, but rides idly thereover, the dog swinging rearwardly and upwardly about its pivot. The weight 52 carried forward by momentum beyond its normal stopping position, immediately swings or "kicks" back, causing the dog 55 to swing said releasing arm so that a lug 57 thereon swings the section 47 away from the opening 25, and thus allows the spring 22 carrying the dog 23 to move the dog out of engagement with the gear 27. This uncoupling action takes place after the platen and handle have been stopped, thus eliminating the danger of overthrow. The bill now being in proper position, may be written upon in the usual manner, the platen being entirely free from the driving mechanism.

In order that the items on the record sheets may not be so close together as to become confusing, the opening 25 in the casing is of sufficient length to permit the dog to remain disengaged from the gear during a portion of the forward stroke of the driver, so that the distance the platen is rotated when moved back to receive a new bill is several line-spaces less than its forward rotation as the driver is returned. Thus when the new bill is inserted, the first line of data thereon will appear several line-space distances apart from the last line of data of the preceding bill on the record sheet. It will be understood that when the dog is moved by its spring 22 away from the gear, the movable section 47 is held by the dog away from the opening 25 until the dog has again been moved into engagement with the gear, at which time the spring 50 returns the section over the opening.

In order to insure that the dog 23 will properly drive the gear 27 and platen in both directions, the dog comprises oppositely inclined teeth which coöperate respectively with two ratchet wheels having oppositely inclined teeth, one tooth of the pawl being operative to drive the gear in one direction, and the other tooth being op-

erative to drive the gear in the opposite direction. The two ratchets may be fixed together in any suitable manner, such as by pins 58 (Fig. 5) and together form the gear 27.

Variations may be resorted to within the scope of the invention, and portions of the improvements may be used without others.

Having thus described my invention, I claim:

1. The combination with a revoluble platen, of a crank or handle normally disconnected from the platen, releasable means to lock said crank and platen together to rotate backwardly and forwardly, a stop to arrest the return stroke of the platen and crank while they remain locked together, and a part connected with the crank to move by momentum after such arrest, and having means to effect an unlocking of the crank and platen.

2. The combination with a revoluble platen, of a crank or handle normally disconnected from the platen, releasable means to lock said crank and platen together for backward and forward rotation, a motor to return said crank to normal position together with said platen, a stop to arrest such return stroke effected by said motor, whereby said platen and crank remain locked together after their arrest, a weight connected to be driven by said motor during the return of the crank and platen and to keep moving by its momentum after such arrest of the crank and platen, and means controlled by said weight during such subsequent movement, for effecting an unlocking of the crank and platen.

3. The combination with a revoluble platen and a driver normally disconnected therefrom, of means dependent upon the forward movement of the driver to couple it to the platen, a motor to return the platen and driver, a stop to arrest the platen and driver, a gate normally in ineffective position, means dependent upon the movement of said driver to move said gate to effective position to prevent a releasing movement of said coupling means, a weight connected to said driver to operate by momentum after the driver is arrested at its return stroke, means operated by said weight to open said gate, and means effective to operate on said coupling means to release the driver from the platen when said gate is open.

4. The combination with a rotary platen and a driver having a forward and return movement from a normal position of rest, of a stop to limit the return movement of the driver, means to automatically connect the driver with the platen after the driver has moved forwardly through a predetermined distance from its starting position, and thereby cause the platen to be rotated by the driver during the remainder of the for-

ward movement of the driver, a motor to rotate the platen in the reverse direction and through said connecting means to return the driver until arrested by said stop, and means 5 to automatically disconnect the driver from the platen, said disconnecting means comprising a weighted trip device moving with the platen and driver during the return of the latter and operable by its momentum 10 when the driver and platen are brought to rest to effect the release of the driver from the platen to permit the latter to be rotated independently of the driver.

5. The combination with a rotary platen, 15 of a driver, connecting means between the driver and platen for rotating the platen in one direction, said means comprising a dog operated by the driver and a toothed wheel connected to the platen, means for holding 20 the dog in engagement with said wheel, a motor to automatically rotate the platen in the reverse direction and return the driver, and releasing means including a weight operated by its momentum to release the dog 25 from said wheel after the platen has been brought to rest at the completion of the return movement of the driver.

6. The combination with a rotary platen, 30 of a driver having a limited advance and return movement from a normal position of rest, a dog connected to be operated by the driver, a rack connected to rotate with the platen, said dog moving idly with the driver during the initial portion of its advance 35 movement, means to move the dog into engagement with its rack, and hold it in such engagement during the remainder of the advance movement of the driver and thereby rotate the platen backwardly or in an anti- 40 line-spacing direction, a motor to automatically rotate the platen in a forward direction and through said dog to return the driver, a stop to limit the return movement of the driver and thereby also arrest the platen, 45 additional means to hold the dog in engagement with its rack after the platen, during the return of the driver, is advanced beyond the point at which the dog was engaged therewith, whereby the platen is rotated forwardly through a greater distance than 50 backwardly, and means to automatically release the dog from its rack when the platen has completed its forward movement and the driver has been brought to rest by engagement with its stop.

7. The combination with a rotary platen, 55 of a driver having a limited advance and return movement from a normal position of rest, a dog connected to be operated by the driver, a rack connected to rotate with the platen, said dog moving idly with the driver during the initial portion of its advance movement, means to move the dog into engagement with its rack, and hold it 60 in such engagement during the remainder

of the advance movement of the driver and thereby rotate the platen backwardly or in an anti-line-spacing direction, a motor to automatically rotate the platen in a forward direction and through said dog to 70 return the driver, a stop to limit the return movement of the driver and thereby also arrest the platen, additional means to hold the dog in engagement with its rack after the platen, during the return of the driver, 75 is advanced beyond the point at which the dog was engaged therewith, whereby the platen is rotated forwardly through a greater distance than backwardly, means to automatically release the dog from its rack 80 when the platen has completed its forward movement and the driver has been brought to rest by engagement with its stop, said dog-releasing means comprising a throw-off device to move said last-mentioned holding 85 means out of engagement with the dog, and an inertia-controlled trip device operated by its inertia after the driver has been brought to rest to actuate said throw-off device. 90

8. The combination with a rotary platen, of a driver, a toothed wheel connected to rotate with the platen, a dog operated by the driver and spring-held off said wheel while the driver is in its normal position of rest, 95 means to hold the dog in engagement with the said wheel, said means comprising a stationary holding section operative after the driver has been advanced through a predetermined distance from its normal position of rest to hold the dog against said wheel during the remainder of the advance movement of the driver, and during the return of the driver to the point at which the dog was engaged with the wheel, a movable 100 dog-holding section operative to hold the dog in driving engagement with its wheel during the remainder of the return movement of the driver, a motor to drive the platen and return the driver, and means 105 operable when the driver has completed its return movement to automatically actuate said movable holding section to release the dog and thereby permit the platen to be rotated independently of the driver. 110

9. The combination with a rotary platen, of a driver, a toothed wheel connected to rotate with the platen, a dog operated by the driver and spring-held off said wheel while the driver is in its normal position of rest, means to hold the dog in engagement with the said wheel, said means comprising a stationary holding section operative after the driver has been advanced through a predetermined distance from its normal position of rest to hold the dog against said wheel during the remainder of the advance movement of the driver, and during the return of the driver to the point at which the dog was engaged with the wheel, a movable 120 125 130

dog-holding section operative to hold the dog in driving engagement with its wheel during the remainder of the return movement of the driver, a stop to limit the return movement of the driver, means to automatically release the dog from said wheel, comprising a throw-off device, and a weighted kicker or trip device having a flexible connection with the driver permitting it to be vibrated by its momentum after the driver has been brought to rest against said stop, and operable by said vibration to actuate the throw-off device and thereby release the dog to permit the platen to rotate independently of the driver.

10. The combination with a rotary platen, of a platen-rotating mechanism operable at each complete cycle of operations to rotate the platen backwardly through a predetermined fixed distance and then rotate the platen forwardly through a predetermined fixed distance greater than its backward rotation, said mechanism comprising a driver having an advance and return movement from its normal position of rest, a stop to limit the return movement of the driver, a driving wheel connected to rotate with the platen, a dog movable into and out of engagement with said wheel, a speed-multiplying connection between said dog and the driver, said dog normally held out of engagement with the wheel while the driver is in its normal position of rest means to hold the dog in engagement with its wheel comprising a movable holding section inoperative during the initial advance movement of the driver, and a fixed holding section operable to hold the dog in connection with the driving wheel during the remainder of the advance movement of the driver and during the corresponding portion of the return movement of the driver, said movable holding section operable during the remainder of the return movement of the driver where- 45 by the platen is rotated forwardly a greater distance during the return of the driver than it is rotated backwardly during the advance of the driver, a spring motor to drive the platen in a forward direction and 50 return the driver to said stop, and means operable automatically to move said dog-holding section at the completion of the return movement of the driver to release the dog and permit the platen to be rotated independently of the driver.

11. In a typewriting machine, the combination with a rotary platen, of platen-driving means having a limited back and forth movement and operable to rotate the platen in one direction, a spring to rotate the platen in the opposite direction, and a tape to limit the rotation of the platen by said driving means.

12. In a typewriting machine, the combination with a rotary platen, of a driver to

rotate the platen a predetermined fixed distance in one direction, a returning spring operable to rotate the platen in the reverse direction and to return the driver, and a tape connected at its opposite ends respectively to a part rotating with the platen and a stationary part, and being of such length and so arranged that it limits and determines the extent of rotation of the platen by the driver.

13. In a typewriting machine, the combination with a rotary platen, of a driver to rotate the platen a predetermined fixed distance in one direction, returning springs operable to rotate the platen in the reverse direction and to return the driver, one of said springs connected at its opposite ends respectively to a part rotating with the platen and a stationary part, whereby the spring also serves to limit and determine the extent of rotation of the platen by the driver, and a stop to limit the return movement of the driver and thereby determine its normal position of rest, said stationary part being adjustable to adjustably determine the distance through which the platen may be rotated by said driver.

14. The combination with a platen, of a manually operable platen-driver having an advance and return movement, a dog, a dog-carrying member mounted for rotation about the platen axis, a toothed wheel connected to rotate with the platen, means forming a driving connection between the dog-carrying member and said driver, means providing a stationary holding surface for holding the dog in driving engagement with said wheel as the driver advances and returns, a spring for rotating the platen and returning the driver, and means to shift a section of said surface to release the dog as the driver completes its return movement.

15. The combination with a platen, of a manually operable platen-driver having an advance and return movement, a dog, a dog-carrying member mounted for rotation about the platen axis, a toothed wheel connected to rotate with the platen, means forming a driving connection between the dog-carrying member and said driver, said driving connection comprising a flexible band and a guide pulley over which the band runs, means for holding the dog in driving engagement with said wheel as the driver advances and returns, a spring for rotating the platen and returning the driver, and means to automatically release the dog as the driver completes its return movement.

16. The combination with a rotary platen and platen axle, of means to rotate the platen through predetermined fixed distances first in one direction and then in the opposite direction, said means comprising a driving dog, a dog-carrying member loosely mounted for rotation on the platen axle, a

- toothed wheel with which the dog may engage, a casing inclosing said dog-carrying member and wheel, and providing a means to hold the dog in engagement with the 5 wheel, a driver connected to said dog-carrying member for rotating the latter and thereby by rotating the platen in one direction, means to return said dog-carrying member and rotate the platen, said returning means 10 comprising a spring connected to the said dog-carrying member and casing respectively, and thereby limiting the rotation of said member, and means to automatically release the dog from said member.
- 15 17. The combination with a rotary platen and platen axle, of means to rotate the platen through predetermined fixed distances first in one direction and then in the opposite direction, said means comprising 20 a driving dog, a dog-carrying member loosely mounted for rotation on the platen axle, a toothed wheel with which the dog may engage, a casing inclosing said dog-carrying member and wheel, and providing 25 a means to hold the dog in engagement with the wheel, a driver connected to said dog-carrying member for rotating the latter and thereby rotating the platen in one direction, means to return said dog-carrying member 30 and rotate the platen, said returning means comprising a spring connected to the said dog-carrying member and casing respectively, and thereby limiting the rotation of said member, and means to automatically 35 release the dog from said member, said casing comprising a rotatably adjustable end plate or cap to which the spring is connected to adjustably limit the rotation of the platen by said driver, and a graduated index to 40 indicate the number of line-space distances through which the platen may be rotated by the driver.
18. In a typewriting machine, the combination with a platen, of a driver arranged 45 to rotate the platen a predetermined fixed distance in one direction and then return it, and a tape connected at its opposite ends respectively, to said driver and to a stationary part, said tape being of such length and 50 so arranged that it limits and determines the extent of rotation of the platen by the driver.
19. In a typewriting machine, the combination with a platen, of a driver arranged 55 to rotate the platen a predetermined fixed distance in one direction and then return it, a tape connected at its opposite ends respectively, to said driver and to a stationary part, said tape being of such length and so 60 arranged that it limits and determines the extent of rotation of the platen by the driver, and adjusting means for shifting one end of said tape to vary said extent of rotation of the platen by the driver.
- 65 20. In a typewriting machine, the combination with a platen, of a driver arranged to rotate the platen a predetermined fixed distance in one direction and then return it, a tape connected at its opposite ends respectively, to said driver and to a stationary 70 part, said tape being of such length and so arranged that it limits and determines the extent of rotation of the platen by the driver, said stationary part rotatably adjustable to thereby vary the throw of the 75 driver, and a scale to indicate the length of throw of the driver for which said part is adjusted.
21. In a typewriting machine, the combination with a rotary platen, of a driver to 80 rotate the platen a predetermined fixed distance in one direction, a returning spring operable to rotate the platen in the reverse direction, and to return the driver, a tape connected at one end to a part rotating with 85 the platen and wound thereon as the platen rotates, and a stationary part to which the other end of the tape is connected, said tape being of such length and so arranged that as it is wound on said rotating part it limits 90 and determines the extent of rotation of the platen by the driver.
22. In a typewriting machine, the combination with a rotary platen, of a driver to 95 rotate the platen a predetermined fixed distance in one direction, a returning spring operable to rotate the platen in the reverse direction, and to return the driver, a tape connected at one end to a part rotating with the platen and wound thereon as the platen rotates, a stationary part to which the other end of the tape is connected, said tape being of such length and so arranged that as it is wound on said rotating part it limits 100 and determines the extent of rotation of the platen by the driver, said stationary part being adjustable to vary said extent of rotation, and a scale arranged to indicate said 105 extent of rotation.
23. The combination with a rotary platen, 110 of a driver, means to connect the driver to the platen for rotating the platen, a stop to limit the throw of the driver, and means carried with the driver and operable by its momentum to automatically disconnect the 115 driver from the platen when the driver is arrested by said stop, thereby permitting the platen to be rotated separately from the driver.
24. In a typewriting machine, the combination with a platen, of a driver, means to 120 form a positive driving connection between said driver and the platen, a motor to rotate the driver and thereby rotate the platen, a stop to arrest the driver and platen, and a releasing device carried with the driver and moved relatively to the driver by its momentum when the driver is arrested, said releasing device operable by said relative 125 movement to effect a release of the driver 130

from the platen, permitting the latter to be rotated separately from the driver.

25. The combination with a revoluble platen and a platen frame, of a handle, a band connected to said handle, a pulley mounted on said platen frame over which said band runs, a drum or driver mounted to turn around the platen axis and connected to the other end of said band to be driven thereby, means connected with said handle for coupling said drum and platen to rotate together during the initial and return strokes of said handle, a spring to return said drum and platen, and means for automatically uncoupling the driver and platen.

26. The combination with a revoluble platen and a platen frame, of a handle, a band connected to said handle, a pulley mounted on said platen frame over which said band runs, a drum or driver mounted to turn around the platen axis and connected to the other end of said band to be driven more than an entire revolution thereby, means connected with said handle for coupling said drum and platen to rotate together during the initial and return strokes of said handle, a spring to return said drum and platen, and means for automatically uncoupling the driver and platen.

27. The combination with a revoluble platen and a platen frame, of a handle, a band connected to said handle, a pulley mounted on said platen frame over which said band runs, a drum or driver mounted to turn around the platen axis and connected to the other end of said band to be driven

thereby, means connected with said handle for coupling said drum and platen to rotate together during the initial and return 40 strokes of said handle, a spring to return said drum and platen, means for automatically uncoupling the driver and platen, and means for limiting the stroke of the platen, comprising a second band connected at one 45 end to the drum or driver and anchored at the other end, whereby the driver and platen are permitted to rotate until said second band is wound up.

28. The combination with a revoluble platen and a platen frame, of a handle, a band connected to said handle, a pulley mounted on said platen frame over which said band runs, a drum or driver mounted to turn around the platen axis and connected 55 to the other end of said band to be driven thereby, means connected with said handle for coupling said drum and platen to rotate together during the initial and return strokes of said handle, a spring to return 60 said drum and platen, means for automatically uncoupling the driver and platen, means for limiting the stroke of the platen, comprising a second band connected at one 65 end to the driver or drum and anchored at the other end, whereby the driver and platen are permitted to rotate until said second band is wound up, and means for effecting adjustment of the anchorage, to vary the extent of platen rotations.
